ELECTRIC LAMP

Lawrence Rosenfeld, New York, N. Y.

Application February 17, 1947, Serial No. 729,126

3 Claims. (Cl. 240—81)

1

The present invention relates to an ornamental electric lamp and refers more particularly to a lamp in which the electric light bulb is held in inverted position and surrounded by a translucent diffusing globe.

An object of the present invention is to provide a lamp adapted to hold an electric light bulb in the lowest possible inverted position while at the same time it provides a translucent diffusing member which may be conveniently removed when the bulb must be replaced.

A further object is the provision of means for tilting the bulb, without tilting the translucent globe.

A further object is the provision of a translucent rigid shade supported on the bulb support and tilttable relative thereto.

Still another object is that all of the above functions shall be embodied in a lamp of striking characteristics of appearance being compact and of graceful outline.

In accomplishing the object of the present invention, an ornamental lamp body is provided with a base which preferably embodies the features of my co-pending application filed on April 23, 1947, Serial Number 743,444. Said lamp body may be in the illustrated form of a vase, or alternately may be a cylinder, or any shape desired. Extending upwardly and laterally is a hollow arm adapted to carry interiorly the electric lead wire. Said arm curves back to a substantially central point above the lamp body, comprising a straight terminal portion. An inverted electric bulb socket is mounted at the end of said arm by means of a sleeve slidable on said arm. Said socket is rotatable above the axis of said straight terminal portion and settable in position by means of a set screw.

Above the socket is located a ball socket, mounting a shaft connected to a ball, the shaft comprising a collar and a threaded portion and constituting a support for a substantially flat translucent rigid shade member held in position against the collar by an ornamental nut threaded onto the shaft. The shade member is thus tilttable by reason of the ball socket mount, relative to the electric light bulb socket of the lamp.

A conventional electric light bulb is normally held in the electric light bulb socket, and is surrounded in operating position by a translucent globe mounted substantially immediately above the lamp body and at the base of the arm. In order to replace the electric bulb, the globe must be loosened from its support and the bulb socket rotated about the axis of the straight portion of the arm, permitting the globe to be withdrawn downwardly from around the bulb.

For further comprehension of the invention, and of the objects and advantages thereof, ref-

2

erence will be had to the following description and accompanying drawing, and to the appended claims in which the various novel features of the invention are more particularly set forth.

In the accompanying drawing forming a material part of this disclosure:

Fig. 1 is a side elevation of my improved lamp.

Fig. 2 is a partial vertical sectional view on the line 2—2 of Fig. 1.

Fig. 3 is a horizontal sectional view on the line 3—3 of Fig. 1.

Fig. 4 is a partial vertical sectional view on the line 4—4 of Fig. 2.

Referring now in detail to the drawing, my improved lamp 10 comprises the base portion 11, pedestal portion 12 mounted on the base and a body portion 13 mounted on the pedestal. The body portion 13 is substantially in the shape of a vase comprising a neck portion 14. The electric lead wire 15 is led in through base portion 11 and extends interiorly of body portion 13 and into a C-shaped arm portion 16. Within the body portion 13 the wire 15 is enclosed by a tube 17 which extends longitudinally therethrough. The neck opening 18 of neck portion 14 is closed by washer 19 which is held in position on the top end of the tube 17 by a coupling 20 which threadedly engages tube 17 and which coupling 20 is formed with a T-shaped opening.

Arm 16 may be of any length. It may be extendable and is threaded into the side opening of coupling 20 and the globe mount 21 is threadedly engaged into the upper opening of coupling 20. Arm 16 extends curvishly laterally outward and upward from coupling 20 thence straight upward and finally laterally straight inwardly to a point substantially on the prolongation of the axis of the tube 17 and the body 13. On the straight terminal portion 22 of arm 16 there is rotatably mounted by means of a sleeve 23 the electric light bulb socket 24 which is normally in an inverted vertical position. Sleeve 23 is provided with a set screw 25 by which it may be held against rotation relative to terminal portion 22. Socket 24 is therefore rotatable in a plane perpendicular to the straight terminal portion 22 of arm 16.

Mounted on socket 24 and coaxially thereabove, 50 is the externally threaded pipe 26 whose upper end is formed to constitute a seat for the ball 27. A threaded shaft 28 is connected to the ball 27 and an externally knurled casing 29 threadedly engages pipe 26, constituting therewith and with ball 27 a ball socket mounting for shaft 28. Shaft 28 is further provided with a collar 30 and a translucent substantially flat and rigid shade member 31 is mounted on shaft 28 against collar 30 and held against collar 30 by the ornamental 55 nut 32. Shade member 31 is thus tilttable about

the ball 27, all of such tilting movement being relative to pipe 26 and all other parts of lamp 10 therebelow. An expansion spring 27^a is positioned within the top end of the pipe 26 and operates between a shoulder 26^a formed within the pipe and the ball 27 to urge the ball into frictional engagement with the casing 29 so as to retain the shade member 31 in desired tilted positions.

The translucent globe 33 is mounted by means of a split washer 34 in globe mount 21 and extends approximately concentrically about the spherical portion 35 of electric light bulb 36, having an open upper neck 37 as well as the conventional open lower neck 38. In its operative position the globe 33 is fixed relative to body 13, and may be removed by operation of set screws 40 which engage the split washer 34, when it is desired to replace electric light bulb 36. In such event, the globe 33 is moved upwardly out of its mount 21, set screw 25 is then loosened and socket 24 of bulb 36 is revolved about the axis of portion 22 of arm 16 as indicated in Fig. 4, whereby globe 33 clears mount 21 and may be withdrawn downwardly therepast. As globe 33 passes downwardly, electric light bulb 36 passes through the neck portion 37 and globe 33 is then completely clear of electric light bulb 36 which may now be unscrewed from its socket 24. The operation is reversed in putting the lamp together for operation with a new electric light bulb 36.

It will be noted that lamp 10 is provided with two translucent rigid members, globe 33 and shade 31, shade 31 in its illustrated position of Fig. 1 being perpendicular to the radius of globe 33 passing through the center of its upper neck 37 so as to completely shade neck opening 37, and that shade member 31 is tiltable in all directions relative to neck opening 37 so as to provide less shade and more reflected light in any direction as desired. Convenient means are further provided for the replacing of light bulb 36 within globe 33 as necessary.

It is to be understood that any suitable lamp-shade may be secured in position by the usual ornamental nut 32 and may be swivelled or tilted with respect to the diffusing globe 33.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an electric lamp having a base and a C-shaped arm having one of its end portions attached to the base and extended vertically therefrom, an inverted electric lamp socket positioned at the free end of the other end portion of the C-shaped arm, a light bulb in said socket and depending therefrom, a globe mount on the end portion of the C-shaped arm concentrically below said lamp socket, a globe rested in said globe mount and formed with a top opening through which the bulb extends to the interior of said globe, a shade member tiltably mounted above the lamp socket to shade the top opening of said globe, and means pivotally attaching said

lamp socket to the free end of the other end portion of the C-shaped arm, whereby said globe may be lifted vertically out of said globe mount and pivoted with said light bulb about the pivotal mounting of said lamp socket to a position in which the globe is clear of said globe mount after which the globe may be moved downward free of the bottom of said bulb.

2. In an electric lamp having a base and a C-shaped arm having one of its end portions attached to the base and extended vertically therefrom, an inverted lamp socket positioned at the free end of the other end portion of the C-shaped arm, a light bulb in said socket and depending therefrom, a globe mount on the one end portion of the C-shaped arm concentrically below said lamp socket, a globe rested in said globe mount and formed with a top opening through which the bulb extends to the interior of said globe, and means pivotally attaching said lamp socket to the free end of the other end portion of the C-shaped arm, whereby said globe may be lifted vertically out of said globe mount and pivoted with said light bulb about the pivotal mounting of said lamp socket to a position in which the globe is clear of said globe mount after which the globe may be moved downward free of said bulb.

3. In an electric lamp having a base and a C-shaped arm having one of its ends attached to the base and extended vertically therefrom, a globe having an open top mounted on the attached end of the C-shaped arm, an inverted lamp socket pivotally mounted on the other end of the C-shaped arm and having a light bulb depended therefrom and into the open top of said globe, an externally threaded pipe extended vertically upward from said socket and having its top end formed with a seat for a ball, a ball engaging said seat, a casing threaded engaged upon said pipe over said ball for holding the ball in position on the seat and formed with a top opening, a threaded shaft extending vertically from said ball and freely through said top opening of said casing and being tiltable with said ball to various inclined positions, and a shade member on said threaded shaft for shading the top opening of said globe in all tilted positions of said shaft.
